UNITED STATES PATENT OFFICE.

PHILIP V. COHN, OF MONTCLAIR, NEW JERSEY, AND THOMAS H. NEWTON, OF EAST-HAMPTON, MASSACHUSETTS, ASSIGNORS TO UNITED BUTTON COMPANY, OF NEW YORK, N. Y., A CORPORATION OF NEW YORK.

SOCKET MEMBER FOR SNAP-BUTTONS.

1,283,081.

Specification of Letters Patent. Patented Oct. 29, 1918.

Application filed July 20, 1918. Serial No. 245,925.

To all whom it may concern:

Be it known that we, PHILIP V. COHN, a citizen of the United States, and a resident of Montclair, in the county of Essex and 5 State of New Jersey, and THOMAS H. NEWTON, a citizen of the United States, and a resident of Easthampton, in the county of Hampshire and State of Massachusetts, have invented certain new and useful Improvements in Socket Members for Snap-Buttons, 10 of which the following is a specification.

The present invention relates generally to buttons or fasteners and has more particularly reference to the socket member of a 15 snap fastener such as is used for gloves and the like.

Socket members of this character are generally made up of several parts called the shell, the spreader washer and the collet, 20 together with an outer member of non-flexible material, such as metal or celluloid, that covers the face of the shell and is bent back around the edge of the members being held either between the shell and the collet or by 25 an upset portion of the collet. In either case, the outer member overlaps to such an extent that a considerable quantity of material is used. Furthermore, the edge of the member must be notched so as to form a 30 series of radial prongs in order to admit of the amount of overlapping necessary under such circumstances.

The object of this invention is to produce a structure in which a lesser amount of material is employed in the covering member than was formerly the case, so that a less expensive article is produced; and, at the same time, obviate the necessity of confining 35 said material positively either between the collet and shell or by an upset portion of the collet.

The invention therefore centers around a special construction of collet which consists of a member of sheet material having 45 a body portion and an upstanding circumferential flange, said flange resting on the washer and said body portion having a circumferential ledge and a central aperture, the covering member being bent around the 50 parts into unconfined engagement with the circumferential ledge. Preferably also the said collet is provided with an annular raised bead intermediate the aperture and

the ledge against which the unbroken edge of the covering member abuts. 55

In the accompanying drawings the invention is embodied in a concrete and preferred form in which—

Figure 1 is a perspective view of the collet used in connection with our invention. 60

Fig. 2 is a plan view of the socket member looking in the direction of the arrow 2 of Fig. 3.

Fig. 3 is a sectional view on the line 3—3 of Fig. 2. 65

1 indicates a shell consisting of a disk of sheet material slightly dished and devoid of any upstanding flange. 2 is the usual spreader washer superposed upon the shell. 3 is the collet consisting of a disk of sheet 70 material constituting a body portion and having an upstanding flange 4 which rests upon the spreader washer and is of sufficient depth to give requisite thickness to the socket member and to afford a square corner 75 to the structure. At its back surface the body portion of the collet is provided with a circumferential ledge 5 and adjacent thereto an annular raised bead 6 is formed, there being an aperture 7 in the center. 8 80 is the covering member for the face of the shell and here of celluloid, said covering member consisting of a disk which is heated and then bent back around the three members and into unconfined engagement with 85 the circumferential ledge. The overlapping of this covering member is so slight that it is unnecessary to notch its edges. In this way, the unconfined and unbroken edge 9 of the covering member abuts against the 90 raised bead. Said bead has the advantage of imparting a finish to the socket member so that the rough unconfined edge is not exposed, and also insures requisite depth to the socket member without unduly thickening the member. It also imparts additional strength to the structure. 95

It will be understood that this socket member is placed on one side of the skin or other material to which it is to be attached, and that an eyelet of well known character is then driven through the skin, said eyelet having a portion entering through the aperture of the collet and between the latter and the spreader washer to 100 105 clinch the parts in position. It is then

ready to receive the "birdcage" snap in a well known manner.

I claim:

1. A socket member for snap fasteners comprising: a shell, a spreader washer and a collet superposed one above the other, said collet consisting of a member of sheet material having a body portion and an upstanding circumferential flange, said flange resting on the washer and said body portion having a circumferential ledge and a central aperture, and an outer member of non-flexible material covering the shell and bent around the three superposed members into unconfined engagement with the circumferential ledge.
2. A socket member for snap fasteners comprising: a shell, a spreader washer and

a collet superposed one above the other, said collet consisting of a member of sheet material having a body portion and an upstanding circumferential flange, said flange resting on the washer and said body portion having a circumferential ledge, an annular raised bead inside the ledge and a central aperture, and an outer member of non-flexible material covering the shell and bent around the three superposed members into unconfined engagement with the circumferential ledge and against the raised annular bead.

Signed at New York city, in the county of New York and State of New York, this 12th day of July 1918.

PHILIP V. COHN.
THOMAS H. NEWTON.
